Design for Steam Table & Hot Air Table Cover

Assigned to J. O. Morse.

Patented Nov. 27th 1855.

Fig. 1.

Fig. 2

UNITED STATES PATENT OFFICE.

JAMES O. MORSE, OF NEW YORK, N. Y., AND JOHN W. ADAMS, OF LEXINGTON, KENTUCKY.

DESIGN FOR A STEAM-TUBE AND HOT-AIR COVER.

Specification forming part of Design No. 744, dated November 27, 1855.

To all whom it may concern:

Be it known that we, JAMES O. MORSE, of the city, county, and State of New York, and JOHN W. ADAMS, of Lexington, in the county of Fayette and State of Kentucky, have invented or produced a new and original Design for Hot-Air and Steam-Tube Covers; and we do hereby declare that the following is a full and exact description of the same, reference being had to the annexed drawings, making a part of this specification, in which—

Figure 1 is a side elevation of a hot-air or steam-tube cover, showing our design. Fig. 2 is a plan or top view of the same.

The cover is formed of four sides, and at the center of each side a circular embellishment, A, is placed. (See Fig. 1.) This embellishment has a circular border formed of scrolls *a* and leaves *b*, placed within circular beads *c c'*. The center of the embellishment or the space within the inner bead, *c'*, is filled with diagonal cross-bars *d*, forming squares, which have vertical and horizontal bars *e* within them. The embellishment A is surrounded by figured fret-work B, which fills a panel, C, and the panel C has a frame or border, D, at each side, and a frame or border, E, at the top and bottom. The side frames or borders, D, have fret-work *f* within them, as shown in Fig. 1, and

the top and bottom frames or borders have cross or checkered work *g h* within them.

The panels and borders or frames described constitute one side of the cover, and the other three sides are precisely similar.

At each corner of the cover, or at the angles formed by the meeting of the sides, there are placed trusses F, one at each corner. These trusses are formed of scrolls *j k*, as shown in Fig. 1. The front surfaces of the scrolls *j* are figured, representing braided or basket work, as shown at *l*, and the front surfaces of the scrolls *k* are of leaf form.

What we claim as new, and desire to secure by Letters Patent, is—

The scrolls *j k* and the figured groundwork *l* on the trusses, and the circular embellishment A and figured fret-work B on the panel C, and also the fret-work in the frame or borders D E, when the whole are arranged as herein shown, to constitute a new and ornamental design for a hot-air and steam-tube cover.

JAMES O. MORSE.
JOHN W. ADAMS.
